DESIGN FOR A HANDBAG FRAME

Charles V. Schulz, New York, N. Y.

Application June 23, 1942, Serial No. 107,310

Term of patent 3½ years

To all whom it may concern:

Be it known that I, Charles V. Schulz, a citizen of the United States of America, residing in New York city, county of New York, and State of New York, have invented a new, original, and ornamental Design for a Handbag Frame, of which the following is a specification, reference being had to the accompanying drawing, forming part thereof, wherein,

I claim:

The ornamental design for a handbag frame, substantially as shown.

CHARLES V. SCHULZ.
